UNITED STATES PATENT OFFICE.

DAVID HENRY GOODE, OF SAPULPA, INDIAN TERRITORY.

FRUIT-CLIPPER.

No. 833,714.

Specification of Letters Patent.

Patented Oct. 16, 1906.

Application filed November 9, 1905. Serial No. 286,587.

To all whom it may concern:

Be it known that I, DAVID HENRY GOODE, a citizen of the United States, residing at Sapulpa, in District 8, Indian Territory, have 5 invented a new and useful Fruit-Clipper, of which the following is a specification.

This invention relates to fruit-clippers.

The objects of the invention are to improve and simplify the construction of such 10 devices; furthermore, to increase their efficiency in operation and to decrease the expense attending their manufacture.

With the foregoing and other objects in view, which will appear as the description 15 proceeds, the invention resides in the combination and arrangement of parts and in the details of construction hereinafter described and claimed, it being understood that changes in the precise embodiment of invention here- 20 disclosed can be made within the scope of the following claims without departing from the spirit of the invention or sacrificing any of its advantages.

In the accompanying drawings, forming 25 part of this specification, Figure 1 is a perspective view of a fruit-clipper constructed in accordance with the invention, showing the manner of using the same upon a bunch of bananas; and Fig. 2 is a side elevation, partly 30 in section, of the improved fruit-clipper.

Like reference-numerals indicate corresponding parts in the different figures of the drawings.

The fruit-clipper of the present invention 35 comprises a pair of handles 1 and 2, which are pivotally connected with each other, as indicated at 3, and are bent laterally at their outer ends to produce a pair of clipping-blades 4 and 5. Each of the handles 1 and 2 40 preferably is formed in its inner side with a longitudinal groove 6.

For the purpose of forcing the handles 1 and 2 apart, so as to separate the blades 4 and 5, an approximately U-shaped spring 7 is 45 fitted between the handles 1 and 2 so as to be disposed in the grooves 6 of said handles. The handle 1 preferably is formed with a perforation 8, through which one end of the U-shaped spring 7 is bent, as shown at 9. 50 After passing through the perforation 8 the spring 7 is bent in the direction of the pivot-

point 3, so as to form an approximately straight resilient portion 10, which is almost parallel with the outer edge of the handle 1. The end of the portion 10 of the spring 7 is 55 reversely bent to form a hook 11, by means of which the device can be suspended from a nail or other support.

As is well known, a bunch of bananas is usually suspended by means of a small cord. 60 If it be desired to hold the improved clipper in position above the bunch of bananas, so that it can be readily detached therefrom when it is desired to sever a banana, the fruit-clipper is pushed against the suspended 65 cord of the bunch of bananas in such manner that said cord enters the tapering entrance-throat 12 between the approximately straight portion 10 of the spring 7 and the back of the handle 1. The portion 10 of the spring 7 70 serves to clamp the suspending-cord of the bunch of bananas firmly against the back of the outer portion of the handle 1, so as to hold the clippers in position to be readily grasped and drawn away from the suspending-cord. As previously explained, the hook 75 11 can be used when the clippers are to be suspended from a nail. It will be apparent, therefore, that the portions 10 and 11 of the spring serve to produce two different gripping members for suspending the clipper 80 when not in use.

In addition to their use as gripping or suspending members the bent portions 9, 10, and 11 of the spring 7 also serve to hold said 85 spring securely within the inner grooves 6 of the handles 1 and 2, so that it is not necessary to employ any independent securing means for preventing the displacement of the spring.

The improved fruit-clipper of the present 90 invention is strong, simple, durable, and inexpensive in construction, as well as thoroughly efficient in operation.

What is claimed is—

1. A fruit-clipper comprising a pair of 95 pivotally-connected handles having angularly-bent blades, and a spring mounted between said handles and having one of its ends extended outward through one of said handles to form a hook.

2. A fruit-clipper comprising a pair of 100 pivotally-connected handles having grooves

in their inner sides, cutting-blades formed integral with said handles, an approximately U-shaped spring fitted into the grooves in the inner sides of said handles, one end of said 5 spring being bent outward through one of said handles and backward toward the pivot-point of said handles to form a straight por-

tion in approximate parallelism with the outer edge of said handle, and a hooked end, for substantially the purposes set forth.

DAVID HENRY GOODE.
